UNITED STATES PATENT OFFICE.

GEORGE A. MEAD, OF MANSFIELD, OHIO, ASSIGNOR TO THE OHIO BRASS COMPANY, OF MANSFIELD, OHIO, A CORPORATION OF NEW JERSEY.

METHOD OF MAKING JOINTS.

1,286,382.

Specification of Letters Patent.

Patented Dec. 3, 1918.

Original application filed June 14, 1917, Serial No. 174,666. Divided and this application filed February 2, 1918. Serial No. 215,202.

To all whom it may concern:

Be it known that I, GEORGE A. MEAD, a citizen of the United States, residing at Mansfield, in the county of Richland and 5 State of Ohio, have invented certain new and useful Improvements in Methods of Making Joints, of which the following is a specification.

This invention relates to the method of 10 securing parts together. This invention is particularly adapted to connecting the adjacent ends of rails by means of a connector for conducting the electric current from one rail to the next, thereby producing the effect 15 electrically of a continuous rail without joint.

Another use to which this invention can be put is that of a method of bonding which can be applied with a minimum amount of 20 physical effort upon the part of the man installing the bonds.

Another use to which this invention is adapted is that of a method by which rail bonds can be installed with practically the 25 same contacting pressure in each case.

Other objects of this invention as relating 30 to its application of this invention will be readily comprehended by those versed in the art from the following description.

This application forms a division of application Serial No. 174,666 filed June 14, 1917.

There are a number of disadvantages in the present type of bonds intended to be attached to the rails by expanding the terminals in holes provided for the same and also in the method of applying such types of bond. One of the objections is that the operator is obliged to exert considerable effort 40 upon the end of a long wrench in compressing the terminal of the bond into a hole in the rail.

The operator soon tires and the result is that the majority of bonds have been 45 slighted and their contact efficiency is low. It is the aim of this invention to minimize the physical efforts and at the same time to employ a means for expanding or compressing the terminal within the hole of a rail 50 which will give uniform results; that is the force will be equal in each case or approximately so and, therefore, having uniform conditions as to size of terminal and size of

hole in rail, the expansion or compression of the bond will be uniform or substantially 55 uniform and the contact efficiency will be substantially equal in all cases.

In order to apply my method to the bonding of rails and secure these benefits thereof, I employ an explosive which is located within the terminal of the bond as a means of creating the expansive force whereby the terminal is made to contact with the rail. This explosive may be in the form of a liquid, a solid, or a gas contained under 60 pressure within a receptacle, but whatever form is used it should be of a sufficiently unstable chemical character to readily explode and suddenly expand under proper conditions. The explosive can form either a fixed 65 part of the bond, that is applied to the bond at the time of manufacture and non-removable, or it may be separate which can be applied to the terminal by the user at the time 70 when he desires to install the bond.

As applied to the bonding of rails the following is a description of the various figures shown in the drawing and my method 75 of applying the same:

Figure 1 shows a sectional end view of a 80 rail and bond terminal, and a compressor positioned upon the rail and bond terminal and shown partially in section.

Fig. 2 shows a bond terminal and rail in section, the terminal being installed in the 85 side face of the ball of the rail, and a compressor for holding the parts together is shown in partial sections.

Fig. 3 shows a side elevation of one form 90 of my bond with one terminal shown in section.

Fig. 4 shows a plan view of the bond shown in Fig. 3.

Fig. 5 shows a side elevation of a second 95 form of my invention but differing from that shown in Fig. 3.

Fig. 6 shows a view of a shell containing an explosive and a priming cap for use with the type of bond shown in Fig. 3.

The bond which I use with my method of 100 bonding rails consists of one or more terminals indicated by numeral 1, united by a conductor 2, which may consist of a flexible copper member or other suitable conducting means. The terminals are attached to the 105 intervening conductor in any suitable man-

ner, such as inserting one end of the conductor 2 in a cavity in the terminal, then squeezing the terminal about the conductor end either cold or while the parts are under 5 heat or both. The terminal is formed with a hole or recess 3 which extends through the head or flange 4 and into the shank 5. The recess 3 is for the reception of a shell containing an explosive and which is shown in 10 Fig. 6 and which may be of the ordinary type of blank cartridge found upon the market, or it may be made specially in order to meet special requirements.

Another form of the bond which I make 15 use of in the application of my method of bonding rails is shown in Fig. 5 and in this form the terminals are charged with the explosive by the manufacturer of the bond. The bond is the same as described for Fig. 3 20 but in Fig. 5 the terminal is loaded with an explosive 10 and the end of the cavity or recess in the terminal is closed by means of a cap 11 and the cap 11 is provided with a primer for detonating the explosive 10.

25 In applying my method to the bonding of rails a hole is first drilled in each rail adjacent to the abutting ends as conditions require. The hole is to be of such a size as to snugly receive the shank 5 of the bond. If 30 the bond is not provided by the manufacturer with its full charge of explosive as shown by the type of bond in Fig. 5 then the type of bond shown in Fig. 3 is used and the charge is applied by the users by inserting 35 in the recess 3 a charge contained in a shell or receptacle as shown by Fig. 6.

The bond terminal and a charge contained therein is now inserted in the hole in the rail provided for the bond terminal, and a 40 compressing or holding tool is applied and such a tool is shown and method of positioning in Figs. 1 and 2. This tool need not be shown in the figures but can be of various forms of construction with the idea 45 of holding the terminal in place in the rail and maintaining a closed end for preventing the escape of the expanding gases within the terminal and having means for detonating or exploding the charge within the terminal.

50 Having properly positioned the bond and the compressor, the explosive charge within the terminal is detonated or exploded, and where the form of compressor tool is used as shown in Figs. 1 and 2, this is accomplished 55 by a light hammer blow on the exposed end of the firing pin 9 or 15 so that the opposite or internal end of the firing pin contacts sharply with the priming cap adjacent the explosive charge.

60 The discharge of the priming cap causes the explosive material contained within the bond terminal to disintegrate or break up through its unstable chemical character and in doing so it forms suddenly a large volume 65 of gas which creates a very great internal

pressure upon the walls of the terminal, thereby causing the bond terminal to expand and contact securely with the walls of the hole in the rail.

The construction and operation of the two 70 forms of compressor tools shown in Figs. 1 and 2 are quite clearly set forth in the drawings and are quite obvious and do not, it is believed, require any extensive description. 75

It will be readily comprehended that the great manual effort in installing the solid terminal type of bond in a rail and which type is the one most commonly used, has been 80 eliminated by my method of applying a bond in which the force required to expand the terminal is produced by an explosive which will break up and produce suddenly a large volume of gases within a confined and limited aperture or recess. 85

It will be clearly seen that my invention is not confined solely to that of installing rail bonds, but can be applied to the installation of rivets, studs, etc., in which the rivet, stud, etc., would be constructed practically as set 90 forth in the drawings and description, that is, the rivet would be apertured for a charge of explosive and then applied as herein described for a bond terminal.

I have herein described and set forth the 95 preferred method of applying bonds to a rail, but I do not wish to be limited to such method as specifically described herein as many modifications may suggest themselves to one skilled in the art which would not depart from the spirit and scope of my invention and I do not wish to be limited beyond my claims and what I claim as new and novel and desire to secure by Letters Patent, is: 100 105

1. The method of making connections to electrical conductors consisting in forming a hole in the conductor, then inserting therein a connecting terminal containing an explosive and then firing the explosive, thereby creating an interior pressure and expanding the terminal into secure contact with the conductor. 110

2. The method of making connections to electrical conductors consisting in forming a 115 hole in the conductor, then inserting therein a connecting terminal provided with a cavity, then inserting in the cavity an explosive and then firing the explosive, thereby creating an interior pressure and expanding 120 the terminal into secure contact with the conductor.

3. The method of making connection to electrical conductors consisting in forming a hole in the conductor, then inserting a conducting terminal therein and then firing an explosive positioned within the terminal to expand the terminal into secure contact with the conductor. 125

4. The method of making connections to 130

electrical conductors consisting in forming a hole in the conductor, then inserting a connecting terminal in the hole and then applying means to the terminal for firing an explosive contained therein.

5. The method of uniting two articles which consists in forming a hole in one of

the articles, then inserting the other article into the hole in the first article and then firing an explosive contained in the second 10 article to expand the second article into secure engagement with the first article.

In testimony whereof I affix my signature.
GEORGE A. MEAD.
